UNITED STATES PATENT OFFICE.

LESTER M. RICH, OF CEDAR RAPIDS, IOWA.

PUMP-CAP.

SPECIFICATION forming part of Letters Patent No. 771,666, dated October 4, 1904.

Application filed April 8, 1904. Serial No. 202,224. (No model.)

To all whom it may concern:

Be it known that I, LESTER M. RICH, a citizen of the United States of America, and a resident of Cedar Rapids, county of Linn, 5 State of Iowa, have invented certain new and useful Improvements in Pump-Caps, of which the following is a full and clear specification, reference being had to the accompanying drawings, in which—

10 Figure 1 is a side elevation of the upper part of an ordinary lift-pump provided with my improvements. Fig. 2 is a vertical section, enlarged, taken through the pump-cap proper; Fig. 3, a vertical section taken at right angles 15 to the line on which Fig. 2 is taken. Fig. 4 is a bottom of a cap. Fig. 5 is a bottom view of the supplemental sliding cap.

The object of this invention is to provide a simple and effective device for keeping covered the hole or slot in the pump-cap in which the plunger-rod vibrates; and it consists of certain novel features of construction herein-after described, and pointed out in the claim appended.

25 Referring to the drawings by letters, *a* designates the pump-cap proper, which is adapted to be attached to the upper end of the pump-cylinder in any suitable manner. At one edge of the cap is formed integral with it the standard *b*, in the upper bifurcated end of which is pivotally mounted the usual operating-lever *c*, whose shorter arm is pivotally connected, as usual, to the plunger-rod *d*. An integral extension of the standard *b* is ex- 30 tended across the top of the pump-cap to form a rib *e*, and through this rib and the top of the pump-cap is formed a slot *f*, which permits the plunger-rod to vibrate as it is vertically reciprocated.

40 Formed integral with the side edges of the rib *e* are flanges *g*, and engaging under these flanges are the lugs *h* of a sliding supplemental cap *i*, said lugs being curved inward under the flanges *g*, so as to prevent the cap *i* 45 from being lifted off the rib. This cap is pro-

vided with a hole *j*, which nicely fits the plunger-rod.

It will be observed that as the plunger-rod vibrates the cap *i* will slide back and forth on the rib and always keep the slot *f* closed, thereby preventing foreign substances that would injure the valve of the plunger falling into the pump-cylinder. To prevent the cap from sticking to the upper flat surface of the guide-rib during frosty weather, its under surface is provided with a series of lugs *k*, which bear and slide upon said upper flat face of the rib on each side of the slot *f*. These supporting-lugs *k* are an important feature, as without them the cap would freeze to the supporting-rib in frosty weather and would either be broken or would bend the plunger-rod.

By forming the guide rib or way as an extension of the standard it will be observed that not only will the guide-rib be in perfect 65 alinement with the plane of movement of the lever, but also will serve to strengthen the cap at the point where the slot *f* would otherwise weaken it.

Having thus described my invention, what 70 I claim as new, and desire to secure by Letters Patent, is—

The combination with a pump-cap and a standard, said pump-cap being provided with a slotted guide-rib, a lever and a plunger-rod, 75 and a sliding cap-plate mounted on the rib and provided with a hole for the plunger-rod coincident with the slot in the guide-rib and on its under side with a series of separated bearing-lugs resting upon the upper side of said guide-rib and serving to support the cap-plate above said surface, for the purpose set forth.

In testimony whereof I hereunto affix my signature, in the presence of two witnesses, this 5th day of April, 1904.

LESTER M. RICH.
